UNITED STATES PATENT OFFICE.

CHARLES LOVERIDGE AND ALLEN E. COX, OF PORTLAND, OREGON.

PRECIOUS-METAL-RECOVERY MACHINE.

Application filed October 6, 1925. Serial No. 60,796.

Our invention relates to machines for the separation and recovery of metals of different specific gravities, from the foreign substances in which they may ordinarily be found in a free state.

One of the purposes for which a device of the character of our invention is primarily used in a commercial way, is for the recovery of the lead shot from the grounds about shooting ranges and the fields of gun clubs.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

20 In the drawings:—

Fig. 1 is a side elevation of the assembled device.

Fig. 2 is a cross sectional, side elevation, of the assembled device.

25 Fig. 3 is a sectional, plan view, taken on line 3—3 of Fig. 1, looking in the direction indicated.

Fig. 4 is a sectional, plan view, taken on line 4—4 of Fig. 1, looking in the direction indicated.

Fig. 5 is a partial, end elevation, taken on line 5—5 of Fig. 1, looking in the direction indicated.

35 Fig. 6 is a partial, end view, taken on line 6—6 of Fig. 1, looking in the direction indicated.

Fig. 7 is a plan view, partially in section of the nozzle outlet of a preferred form of one embodiment of our device as used at the 40 point of the jump riffle.

Fig. 8 is an end view, of the mechanism, shown in Fig. 7.

Fig. 9 is a preferred embodiment of our device as the same is applicable for use in a 45 sluice box wherein the same may be used in conjunction with hydraulic mining, where hydraulic giants are being used.

Fig. 10 shows a form of amalgam plate for use where gold is being recovered and is shown in dotted position in Fig. 2.

50 Fig. 11 is a sectional elevation, taken on line 11—11 of Fig. 3, looking in the direction indicated.

Fig. 12 is an enlarged, sectional view, taken on line 12—12, of Fig. 11, looking in the direction indicated.

Fig. 13 is a partial, sectional view, taken on line 13—13 of Fig. 11, looking in the direction indicated, and is made to further illustrate the mechanism shown in Fig. 12. 60

Like reference characters refer to like parts throughout the several views.

Our machine comprises a structural frame 1, which has suitable cross ties and tie struts for maintaining the same in a rigid working condition; and is preferably mounted on suitable means for moving the same from place to place, which may be skids and shown at 2. 65

Disposed at or near the top of the frame 70 structure is a revolving cylindrical screen 3, properly mounted and supported within the frame structure; the revolving screen is inclined at an angle to facilitate the passage of the material therethrough, and having 75

one or more longitudinal transverse bars 4, to facilitate the agitation of the material being passed therethrough as the screen is revolved. One or more bands 6^a, are disposed upon the inner periphery of the cylindrical 80

screen having a substantial depth to create riffles within the revolving screen. These bands 6^a, will prevent the rapid passage of the material, being treated, through the screen and at the same time will create additional agitation of the materials being 85

treated. The spout 5, is arranged at the inlet end of the revolving screen, into which the material is deposited to be fed into the screen. To facilitate the saturation of the 90

materials deposited within the revolving screen, we have provided a pipe 6, having a discharge outlet 7, disposed along the under side thereof. Water under pressure is supplied to the pipe from a source of supply so 95

that the water is discharged in spray like formation from the openings therefrom and is supplied in sufficient quantity to thoroughly saturate the quantity of material being passed through the screen. 100

The materials to be recovered in most operations are in the finer materials, and one of the objects of the screen is to segregate the coarser material from the fine as an initial operation; the coarser material being 105

discharged from the outlet end 8, of the revolving screen. The finer materials passing through the openings in the screen are deposited upon the slide 9, from whence the same are washed by the water being deposited within the screen and the same are then deposited upon the upper screen 10, which 110

has openings therethrough to facilitate a further segregation of the coarser materials from the fine materials. This screen, as well as the one disposed therewith, have imparted a vanner or jiglike movement to the same to facilitate the feeding of the materials down the sloping surface of the screens and to facilitate the passage of the finer materials therethrough. Disposed at the 10 lower or discharge end of screen 10, is an opening 11, across which the materials of lighter specific gravity will pass; the heavier materials, or the materials of a high specific gravity drop through. A nozzle 12, is disposed immediately below the edge of the opening or jump riffle 11, and discharges water under a fairly high pressure to form a sheet of water upon which the materials of a lesser specific gravity ride and are carried 20 across the opening. Materials of a higher specific gravity drop through the water sheet.

A second screen 13, is disposed below the upper screen 10, and has placed at the lower 25 outlet thereof, a second water jet 14, for the same purpose as heretofore described for the nozzle 12. Side board members 15 and 16, are disposed at the lower end of the screen, to form a restricted opening outlet above 30 the nozzle 12. This is best shown in Fig. 3. A fanlike water discharge is created at the nozzle outlet reaching its maximum supporting value at the outlet from the screen and reaching across the jump riffle 11.

35 An amalgam plate 17, as shown in Fig. 13, and shown in dotted position in Fig. 2, is placed therein and coated with suitable material as mercury, to cause the precious metals, as gold, to be recovered thereupon.

40 A shaft 18, is disposed across the machine and supported upon the frame structure, having an eccentric 19, secured thereto and an eccentric strap 20, secured to the connecting rod 21, and secured to the screen frame 45 by a bracket 22. The shaft 18, imparts a vanner or jiglike movement to the screen upon the rotation of the shaft 18. This shaft is rotated by suitable power means.

The finer and lighter materials that are not 50 recovered, are deposited from the machine through the outlet 23, as best shown in Fig. 2.

All of the items of a high specific gravity that drop through openings or jump 55 riffles 11 and 24, and other items not heretofore separated are deposited upon the inclined table 25, which is inclined to the horizontal in its transverse length and has a rocking motion imparted thereto, the same being 60 supported transversely its length, and has a series of header pipes 26, across the same being supplied with water under a fairly high pressure through an inlet 27, the same leading through outlets 28 and 29, from the inlet pipe and running along either side of the

same so that the outlet pipes 26, are fed from both ends in order that a uniform and steady pressure may be applied. Slotted outlets 30, are provided in cross pipes 26, for discharging therefrom water in a sheetlike formation 70 to further agitate the materials for deposit thereupon to wash the same and to facilitate the passage of the material across the screen; the washing effect being further facilitated by the rocking motion being imparted thereto.

The breadth of openings at the jump riffle locations will depend upon the character of material being treated and the specific gravity of the materials, the breadth will also 80 depend upon the water pressure at the nozzle outlet. To regulate the breadth of opening we have provided slots 31 and 32 in the outlet aprons 33 and 34 through which the threaded pins 35 and 36 work. These threaded pins are in threaded relation with the side walls of the screen frame of the machine and when the breadth of the opening has been determined, the aprons may then be secured in place by tightening the threaded pins so 90 that the head of the same, clamp the aprons in place.

To facilitate the cleaning of the screens and to further facilitate the passage of the materials being treated across the screens, as 95 well as to break up the larger pieces that may be loosely held together, we have provided a means for violently jarring the screens central of their edges. A spring 37, is secured to the base 38, and is maintained 100 in a position central of the edges of the screens. A plunger 39, is disposed above the spring 37, and registers with the inner surface of the spring and is normally held in a quiescent condition. The plunger is held 105 in relationship with the screens by suitable locking nuts 40 and 41, that tend to maintain a spaced relation between the screens and to maintain the same in a working relationship with each other, and to support the same and prevent them from sagging. The plunger 39, has a head on its upper end against which the revolving pawl 43, engages to compress the spring, and as the plunger is depressed the screens are lowered and as the pawl disengages from the head of the plunger the spring is released and in doing so a rebound is imparted to the screens which is of a violent nature. The pawl is secured to the shaft 44, which is 115 adapted to be rotated by suitable driving means from the prime mover, that imparts operation to the device. An opening 45, is provided through which the washed articles of a high specific gravity drop, the breadth 120 of this opening is subject to regulation through the slide 46, which may be changed to regulate the breadth of the opening to meet the working conditions. The washed and recovered materials are finally dropped 125

- upon the screen 48, from where the materials are recovered as a commercial product. A rocking motion is imparted to the structure 25, by supporting the unit as a whole, central 5 of its length as by bearing blocks 50 and 51, having registered therewith the bearing blocks 52 and 53, each set of bearing blocks having a journal pin 54 and 55 about which the structure rocks. The connecting rod 56, 10 is secured to the eccentric strap 57, which engages with the eccentric 58, which is fixed upon the shaft 58^a. Secured to the shaft 58^a, is a driving pulley 59^a, for rotating the shaft. The upper end of the eccentric rod 15 56, is secured to the base of the unit 25, through the means of the bearing block 59, and the journal pin 60. As the eccentric is rotated a rocking motion is imparted to the unit 25.
- 20 A header pipe 61 is supplied with a liquid, as water under pressure, from a source of supply not here shown, which has a series of cross pipes 62, attached thereto and which have caps 63, for closing the ends of 25 the same. The liquid pumped under pressure, is discharged through these pipes 62, and deposited therefrom upon the screens disposed below the same, and over which the materials to be recovered, are made to pass.
- 30 It may be found desirable to use this in conjunction with sluice boxes that are for use in conjunction with hydraulic mining, wherein the sluice box frame 64, has a series of jump riffles disposed therein, as 35 shown at 65 and 66. These jump riffles are operated in a manner similar to that heretofore described, wherein water jets are disposed thereacross for carrying the articles of a lighter specific gravity thereacross and 40 permit materials of a high specific gravity to drop therethrough.
- Another preferred form of embodiment of our device is illustrated in Figs. 12 and 13, wherein a jarring motion or effect is 45 created upon the upper screens which is accomplished by the lever 67, being secured to the frame structure of the machine and which rocks the shaft 44, as the vanner movement is imparted to the screening structure.
- 50 The head 68 disposed above the spring members disposed midway the screening sec-
- tions and attached to the plunger 39, as the rotation of the shaft 44, by the engagement of the lever 67 therewith. The pawl engages on the under side of the head 68 and 55 lifts the same up, as shown in the dotted position in Fig. 12 and Fig. 13, and when the same is disengaged therefrom the spring 37, causes a rebound to the plunger 39 and 60 imparts the jarring movement to the screening members.
- Throughout this specification, we have described the jump riffles as being operated by water sheets, and we have found best results were obtained for this purpose, yet we do 65 not wish to be limited to water, as any fluid, as air, may be utilized for this purpose and we do not wish, therefore, to be limited to the use of water for this purpose.
- While the form of mechanism herein 70 shown and described is admirably adapted to fulfill the objects primarily stated, it is to be understood that it is not intended to confine the invention to the one form of embodiment herein shown and described, as 75 it is susceptible of embodiment in various forms, all coming within the scope of the claims which follow.
- What we claim is:—
1. A precious metal recovery machine, 80 screen sizing elements including flat reciprocating screens having jump gaps at their discharge ends, a stratifying table below the same, means for delivering the material passing through the gaps to said 85 stratifying table, and means for discharging the material passing over the gaps away from the machine.
2. In a precious metal recovery machine, 90 screen sizing elements including flat reciprocating screens having jump gaps at their discharge ends; means causing the light matter passing over the flat screens to pass over the jump gaps and allowing the heavy material to pass therethrough; a stratifying 95 table below the flat screens; means for delivering the material passing through the gaps to said stratifying table; and means for discharging the material passing over the gaps away from the machine.

CHARLES LOVERIDGE.
ALLEN E. COX.
